GLOVE

Edward M. Reece, New York, N. Y.

Application October 17, 1952, Serial No. 21,869

Term of patent 14 years

(Cl. D3—11)

To all whom it may concern:

Be it known that I, Edward M. Reece, a citizen of the United States of America, residing in New York city, county of New York, and State of New York, have invented a new, original, and ornamental Design for a Glove, of which the following is a specification, reference being had to the accompanying drawing, forming part thereof, wherein:

I claim:

The ornamental design for a glove, substantially as shown.

EDWARD M. REECE.
